FAN BLADE ASSEMBLY

Jack Brannan, Pasadena, Calif., assignor to Trade-Wind
Motorfans, Inc., Pico Rivera, Calif., a corporation of
California

Filed May 8, 1961, Ser. No. 65,071

Term of patent 14 years

(Cl. D62—4)

FIG. 1.

FIG. 2.

FIG. 3.

FIG. 1 is a front elevational view of a fan blade assembly showing my new design;

FIG. 2 is a side elevational view; and

FIG. 3 is a rear elevational view thereof.

I claim:

The ornamental design for a fan blade assembly, as shown.
